INVENTOR.

Albert Cousinard.

By *Lacy & Hacey*, Atty's.

UNITED STATES PATENT OFFICE.

ALBERT COUSINARD, OF COURBEVOIE, FRANCE.

FRICITION GRIPPING MEANS.

Application filed December 3, 1925, Serial No. 73,075, and in France May 12, 1924.

This invention relates to friction gripping means, its object being to provide means for holding a movable part in a fixed body firm as soon as the manipulating means there-
5 for is released.

According to the present invention I pro-
vide brake jaws which are normally kept
pressed against a brake drum by resilient
means, said jaws being provided with a
10 central aperture which is greater in length
than in width and two eccentrically dis-
posed apertures whose inner edges are con-
cave to form inclines upon which friction-
ally engage projections integral with the
15 operating handle for the movable part, the
actuating portion of which latter protrudes
into and entirely fills the central aperture
and is integral with the operating handle.

The invention is shown by way of example
20 as applied to the window of an automobile,
in the accompanying drawings in which:

Fig. 1 is a longitudinal section through
the axis of the handle and

Fig. 2 is a cross section on the line A—B
25 of Fig. 1.

In principle the present arrangement con-
sists of a drum 1 having a shaft 2 to which
is secured the handle 3. Two driving mem-
bers 4 carried by the shaft 2 actuate the
30 brake jaws 5 during their rotary movement,
such members 4 bearing on the inclined sur-
faces 6 of the jaws so freeing them from the
drum 1 and thereby compressing the
springs 9.

35 The brake jaws 5, being thus brought
closer together, can be turned by the handle
3 which will cause the pinion 8 to rotate and

operate the movable member to which it is
connected by chain or gearing.

The operation of the device is as follows:

When the handle 3 is released, the springs
9 press the jaws 5 into contact with the
periphery of the drum 1 causing prelimi-
nary frictional contact while, when pressure
is applied to the pinion 8 this presses apart
45 the jaws 5 causing still greater friction, this
being effected by means of the two plates
7 so that any movement of the movable part,
independently of the handle is impossible and
the greater the pressure applied the stronger
50 will be the frictional grip of the jaws 5.

It is to be understood that the invention
is applicable to any apparatus where it is
required to secure a moving member in a
fixed part and that the minor details may
vary within the scope of the appended
55 claim.

I claim:

Friction gripping means consisting of a
brake drum, brake jaws provided with a
60 central aperture which is greater in length
than in width and with two eccentrically
disposed apertures whose inner edges are
concave, springs between the jaws pressing
them apart and into contact with the drum,
65 a movable part, and projections carried by
the movable part and playing in the aper-
tures in the jaws to engage the concave
edges of said apertures and withdraw the
jaws from the drum.

Signed at Paris, in the County of Seine,
France, this nineteenth day of November
1925.

ALBERT COUSINARD.
